UNITED STATES PATENT OFFICE

JOSEPH H. FREEDLANDER, OF NEW YORK, N. Y.

DESIGN FOR A TRAFFIC STANDARD

Application filed July 10, 1931. Serial No. 40,482. Term of patent 7 years.

To all whom it may concern:

Be it known that I, JOSEPH H. FREEDLANDER, a citizen of the United States, residing at New York, in the county of New York and State of New York, have invented a new, original, and ornamental Design for a Traffic Standard, of which the following is a specification, reference being had to the accompanying drawings, forming a part thereof.

Figure 1 of the drawings is a front elevation of the traffic standard. Figure 2 is a side elevation of the same.

I claim:

The ornamental design for a traffic standard, as shown.

JOSEPH H. FREEDLANDER.
